UNITED STATES PATENT OFFICE

2,569,427

COLLAPSIBLE SUPPORT FOR IRONING TABLES

Howard B. Rich, Carrollton, and Andrew Green, Worthville, Ky., assignors to Howard B. Rich, Inc., a corporation of Kentucky

Application February 2, 1949, Serial No. 74,196

2 Claims. (Cl. 38—117)

1

This invention relates to a collapsible ironing table, and more particularly to the supporting framework or chassis of an ironing table or board, or the like.

An object of this invention is to provide a firm and strong collapsible supporting structure or chassis for an ironing table.

A further object of this invention is to provide a framework for an ironing table in which all supports fold against the underside of the table or board when the chassis is collapsed.

A further object of this invention is to provide a framework for an ironing table in which all parts of the chassis are held firmly in a stable position when the table chassis is actuated to board supporting position.

A further object of the invention is to provide an improved arrangement of tension members whereby the legs of the board chassis will give firm and rigid support to the board when in ironing position.

The above and other objects and features of the invention will in part be apparent and will in part be obvious from the following detailed description and the drawings, in which:

Figure 1 is a perspective view showing an ironing table or board having a supporting structure or chassis constructed in accordance with an embodiment of this invention, the chassis being shown in upright or ironing position.

Fig. 2 is a bottom plan view of the table shown in Fig. 1, with the chassis in collapsed or storage position.

Fig. 3 is a view in section, taken along a line III—III in Fig. 2, showing one of the tension members.

Fig. 4 is a view in section, taken along a line IV—IV in Fig. 2.

In the following detailed description and the drawings, like reference characters indicate like parts.

As shown in Fig. 1, the ironing table includes a board 10, here shown as a metal sheet having a stiffening flange 11 extending around the periphery of and forming a border for the board. Strengthening frame members 12 extending lengthwise of the board 10 are fixed to the underside of the board as by riveting. The board is further strengthened and rigidified by cross members 13, which are secured to members 12 and the board by suitable means such as rivets. The ends of the cross members may be secured to the border flange 11 by screws 13' or the equivalent. The board 10 being of metal may be perforated as shown in customary manner.

The board chassis includes a pair of legs 14 and a leg 15 at the rear and front ends of the board, respectively. The upper ends of the rear legs are pivotally secured to a cross-brace 16, the ends of which are flanged to accommodate

the pivot pins of the legs. The rear legs are braced by a pair of diagonal braces 17 and 18. The ends of these braces are so shaped that they are interchangeable and can be used on either "right" or "left" side of the board chassis. The upper ends of these diagonal braces 17 and 18 are secured to the pivot pins 19 which secure the legs to flanges on cross brace 16 and the lower ends thereof are secured to struts 20 and 21, respectively. Struts 20 and 21 are secured to the respective legs 14 at the rear of the chassis. An oval ring 22 embraces diagonal braces 17 and 18 at the point where they cross each other and tends to rigidify these braces.

The front leg 15 includes a pair of members 23 joined at their lower or free ends to form a crutch-like structure. The upper ends of leg members 21 are pivotally attached to a bracket 22 secured to the longitudinal frame members 12.

As shown in Figs. 1 and 2, the front and rear legs 15 and 14 are foldable between an extended or operative position shown in Fig. 1 where the legs can support the board 10 and a folded or collapsed position in which the legs rest against the bottom of the board so that the table can conveniently be stored (Fig. 2).

The compression braces or struts 20 and 21 are pivoted to rear legs 14, an end of each strut being pivoted to one of the legs 16 at a point between the ends of the leg. Opposite ends of struts 20 and 21 are joined to the board by toggle links 24. A handle 25 is mounted between and secured to toggle links 24 and may be used to operate the toggle linkage. When the table is in upright or operative position, upper ends 26 of struts 20 and 21 bear on the lengthwise frame members 12 (Fig. 1). To collapse the board structure, handle 25 is pulled outwardly from the bottom of the board until the toggle linkage (Fig. 2) is moved past dead center, at which time the legs and struts are released and can be folded.

As shown in Fig. 1, upper ends of rear legs 14 and cross-braces 17 and 18 are pivoted to bracket 16. The lower end of each of the cross braces 17 and 18 is pivoted to one of the braces as indicated at 27; thus when the board chassis is moved to the position shown in Fig. 1 the rear legs are spread, and when moved to collapsed position the cross braces 17 and 18 cause the rear legs to contract or move towards each other.

The crutch-like front leg is braced by a pair of tension members 28 when the table or board is in raised position. Tension members 28 extend between rear legs 14 and the lower ends of members 23 of leg 15. To further rigidify the board chassis and give firmness of support to the legs thereof when the board is in the position shown in Fig. 1, upper tension members 29 are provided. A tension member 29 is secured adjacent the upper end of each leg member 23.

The tension members extend through brackets 31 secured to member 12. These tension members are disposed on the adjacent inner faces of leg members 23 and extend forwardly towards the toggle handle 25. Each tension member 29 is provided with an enlarged head 32 to keep it from pulling through bracket 31 when the table is in the position shown in Fig. 1. Tension members 29 are bowed upwardly so that they will move through brackets 31 freely and without binding when the table assembly is moved to or from collapsed position and to render them resilient.

When the board is mounted in the position shown in Fig. 1 and a load is put on it as when ironing is being done, members 23 of leg 15 are subjected to a bending load. The lengths of tension members 29 are such that they are strained in tension, and this strain tends to bend the legs in the opposite direction from which they would be bowed by the load. Therefore, the pull of tension members 29 on leg members 23 offsets the bending strain imposed by the load on the ironing board, thereby relieving them of undue strain and also making the chassis, legs and board structure firm and rigid.

Details of the mounting of the tension members are shown in Figs. 3 and 4. As shown in Fig. 3, each tension member 29 is equipped at one end with an eye 34 that fits about a pivot pin 35 fixed to one of the front leg members 23, while the other end of member 29 extends through an opening in bracket 31. The bracket 31 is fixed to the underside of one of the frame members 12.

The end of each elongated tension member 28 at the point where secured to leg members 21, is provided with an eye 36 through which a pivot pin 37 (Figs. 1 and 2) extends. Pivot pin 37 is located near but spaced from the free end of the crutch-like front leg.

The opposite end of each tension member 28 extends through a clip 38 which, as shown in Fig. 4, is held between one of the rear legs 14 and its associated strut. Each of pivot pins 39 which link legs 14 and the struts also extends through one of the clips 38 to support the clip. The tip of each tension member has an enlarged head 41 (Fig. 2) and bears against the clip 38 when the framework is in table-supporting position. The tension members 28 hold and confine legs of the table to the position shown in Fig. 1.

While the table top 10 is shown as being of metal, it will be appreciated that a top of wood of the usual size and shape can be substituted for the metal top, if desired, in which case brackets 14 and 22, angles 33, and angles 42, which support a pivot for toggle links 24, can be attached directly to the board instead of being attached, as here shown, to frame members for the metal top 10.

The device described above and illustrated in the drawings is subject to variation within the scope of the appended claims.

Having described our invention, what we claim as novel and desire to secure by Letters Patent is:

1. A collapsible ironing table which comprises a board having front and rear ends, a pair of rear legs pivoted to the underside of the board adjacent the rear end thereof, a front leg pivoted to the underside of the board at a point between the ends thereof, means for holding the rear legs in spaced relation to each other, a ten-

sion member extending between the front leg and the underside of the board at a point forward of the pivot for the front leg, a pair of elongated tension members, each of said elongated tension members being secured to one of the rear legs at a point between the ends thereof and to the front leg at a point near the foot thereof, a toggle linkage comprising struts and links secured to each other, the links being secured to the board and the struts to said rear legs, the length of the links and struts in straight line position being greater than the distance between the points of attachment to said rear legs and board whereby a toggle joint is formed at the point where the struts and links are attached to each other, said struts and toggle links being swingable across the break point of the toggle joint whereby when the legs are moved to upright position, the toggle links lie against the underside of the board and above the break point and when collapsed the toggle links are free to swing away from the break point to a collapsed position in which the struts and legs are substantially parallel with the board, said front leg when upright being subjected to a bending load, the tension member extending between the front leg and the board acting to offset the bending load when the board is loaded.

2. A collapsible ironing table which comprises a board having front and rear ends, a pair of legs pivoted to the underside of the board adjacent the rear end thereof, a front leg pivoted to the underside of the board at a point between the ends thereof, means for holding the rear legs in spaced relation to each other, a tension member extending between the front leg and the underside of the board at a point nearer the front end thereof than the pivot of the front leg, a toggle linkage comprising struts and links secured to each other, the links being secured to the board and each strut being secured to one of the rear legs, a pair of elongated tension members, one end of each tension member being secured to the front leg at a point near the foot thereof, the other end of each tension member being linked to one of the struts and to one of the rear legs at a point spaced between the ends of said one of the rear legs, the length of the links and struts in straight line position, being greater than the distance between the points of attachment to said rear legs and board, whereby a toggle joint is formed at the point where the struts and links are connected to each other, said struts and toggle links being swingable across the break point of the toggle joint, whereby when the legs are moved to upright position, the toggle links lie against the underside of the board and above the break point, and when collapsed the toggle links are free to swing away from the break point to a collapsed position in which the struts and legs are substantially parallel with the board.
